UNITED STATES PATENT OFFICE.

JOHN VOLLMER, OF ESSEN, GERMANY,

GUN BARREL BUILT OF AN A-TUBE AND A BREECH PIECE.

1,404,558.

Specification of Letters Patent. Patented Jan. 24, 1922.

Original application filed December 3, 1920, Serial No. 428,086. Divided and this application filed June 6, 1921. Serial No. 475,393.

To all whom it may concern:

Be it known that I, JOHN VOLLMER, residing at Essen, Germany, a citizen of the German Republic, have invented a certain new 5 and useful Improvement in a Gun Barrel Built of an A-tube and a Breech Piece, for which I have filed an application in Germany, dated May 31, 1917, and of which the following is a specification.

10 My invention relates to gun barrels built of an A-tube and a breech-piece. The breech-piece is formed with a jacket portion which screw-threadedly engages the A-tube.

This application is a division of my co-pending application, Serial No. 428,086, filed December 3rd, 1920.

15 The object of this invention is to provide such a connection between these two parts of the gun barrel as will contain sufficient 20 resistance to the stresses set up upon firing, with as little weight as possible with the connecting parts, at the same time effectually sealing the joint between the composite parts of the gun barrel.

25 The various features of the invention will be more clearly described and illustrated in the accompanying drawings in which:

Fig. 1 is a longitudinal section of a portion of a gun barrel constructed in accordance with my invention, and

30 Fig. 2 is a transverse section on line 2—2 of Fig. 1.

The gun barrel consists of a double A-tube A A' and a breech-piece B. The 35 breech-piece is formed with a jacket portion b' which envelopes the rear portion of the A-tube.

The connection between the breech-piece and the A-tube is obtained by screw-threaded engagement between the two and for this 40 purpose the layer A' of the A-tube is provided with screw-threads a² and the jacket portion b' is provided with corresponding screw-threads b².

45 The breech-piece is provided with a slot b³ to accommodate the breech-block and a loading aperture b⁴.

A cylindrical wall b⁷ of the bore of the jacket portion b' which receives the A-tube, 50 is sloped off into a rear face b⁵ of the bore, by an arc b⁶ struck with a comparatively long radius, the said slope commencing at a point situated in the rear of the end face a³ of the layer A of the A-tube.

55 The outer layer A' of the A-tube is pro-

vided with extensions a⁵ of suitable shape to fill the space left between the end face a³ of the inner layer A of the A-tube and the rear face b⁵ of the breech-piece. In order that proper clearance may be provided for the 60 screw-threaded connection between the breech-piece and A-tube, to enable the connection to be put under the proper tension, the extensions a⁵ are made of such a length that they stop short of the face b⁵ of the 65 breech-piece when the breech-piece assumes its correct position relative to the A-tube.

The breech-piece is provided with undercut grooves b⁸ to accommodate covering strips F which strips are adapted to close 70 the stresses or intervals E left between the extension a⁵ and the faces b⁵. These strips F run parallel to the front face of the breech-slot and bear against the rear face a³ of the liner A. These strips are so disposed that they cannot protrude into the breech-slot and endwise motion of the strips F is prevented in screws G. These strips prevent the entrance of dirt into the intervals E and effectually prevent the liner A 75 80 from setting back into the breech-slot b².

Owing to the fact that the wall b⁷ of the jacket portion b', instead of making a sharp or slightly rounded angle with the face b⁵, is sloped off into the latter with an arc 85 struck with a long radius, the A-tube is permitted to retain its full diameter right up to its rear face. This structure offers great resistance for the breech-piece to cracking at the dangerous section where the wall b⁷ 90 merges into the face b⁵ and sufficient strength to the A-tube up to its rear end to prevent expansion under pressure of the powder gases, together also with the least weight possible of the parts in question. 95

Having thus described my invention, what I claim is:

1. A composite gun barrel comprising a breech-piece and an A-tube, said breech-piece being provided with a screw-threaded bore for the reception of the end of the A-tube, the rear face of said bore being arc-shaped, extensions formed on the rear end of the A-tube corresponding in shape to the arc-shaped rear faces of the bore and 100 of such length as to leave a space between the rear face of the bore and said extensions and separate covering strips running parallel to the front face of the breech-slot, 105 as and for the purpose described. 110

2. A composite gun barrel comprising a breech-piece and an **A**-tube comprising an outer member and a liner, said breech-piece being provided with a bore for the reception of the **A**-tube, the cylindrical wall of the said bore being sloped off into the rear face of the said bore by an arc struck with a large radius, the said slope commencing at a point in the rear of the end face of the liner of the **A**-tube and filler pieces in the rear portion of the bore of the breech-piece, said filler pieces being formed by extensions on the **A**-tube.

3. A composite gun barrel comprising a breech-piece and an **A**-tube comprising an outer member and a liner, said breech-piece being provided with a bore for the reception of the **A**-tube, the cylindrical wall of said bore being sloped off into the rear face of the said bore by an arc struck with a large radius, the said slope commencing at a point in the rear of the end face of the liner of the **A**-tube and filler pieces in the rear portion of the bore of the breech-piece, said filler pieces leaving spaces between them and the rear face of the bore of the breech-piece, a wedge-slot in said breech-

piece and strips covering said spaces towards said wedge-slot and running parallel to the front face of said wedge-slot.

4. A composite gun barrel comprising a breech-piece and an **A**-tube comprising an outer member and a liner, said breech-piece being provided with a bore for the reception of the **A**-tube, the cylindrical wall of said bore being sloped off into the rear face of the said bore by an arc struck with a large radius, the said slope commencing at a point in the rear of the end face of the liner of the **A**-tube and filler pieces in the rear portion of the bore of the breech-piece, said filler pieces being formed by extensions on the **A**-tube, said extensions leaving spaces between them and the rear face of the bore of the breech-piece, a wedge-slot in said breech-piece and strips covering said spaces towards said wedge-slot and running parallel to the front face of said wedge-slot.

The foregoing specification signed at 50
Essen, Germany, this 21st day of April,
1921.

JOHN VOLLMER.
